UNITED STATES PATENT OFFICE.

JESSE H. HARRISON AND MATHEW WALKER, OF MANLY, IOWA.

SAFETY-APPLIANCE STEP.

Application filed May 11, 1923. Serial No. 638,296.

To all whom it may concern:

Be it known that we, JESSE H. HARRISON and MATHEW WALKER, citizens of the United States, residing at Manly, in the county of Worth and State of Iowa, have invented a new and useful Safety-Appliance Step, of which the following is a specification.

This invention relates to railway car steps, the primary object of the invention being to provide an extension step so constructed and mounted as to be automatically moved into and out of operation by the movement of the usual vestibule floor door.

Another object of the invention is to provide a device of this character which will hold the extension step in a position adjacent to the lowermost stationary step of the car so that the same will be held out of view and in a position to prevent damage of the step by its contact with switch controlling levers or the like mechanism positioned at the sides of railway tracks.

A still further object of the invention is to provide a movable step and operating means that may be readily and easily applied to the usual car step construction now in use, eliminating the necessity of making extensive alterations in the usual step construction to install the same.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view disclosing a car step equipped with an extension constructed in accordance with the invention.

Figure 2 is a rear elevational view thereof.

Referring to the drawings in detail, the reference character 5 designates the side members of a car step construction, the 50 step sections being indicated at 6.

The reference character 7 designates the usual vestibule floor door of a car that usually swings in a vertical plane to permit the use of the steps.

55 The door 7 is mounted on the shaft 8 that moves in the bearings 9 so that move-

ment of the door 7 will result in a relative movement of the shaft 8. At one end of the shaft 8 is an arm 10 secured to the shaft and extending downwardly therefrom the 60 arm having pivotal connection with the link member that in turn is connected to the uppermost arm 12 of the lazy tong 13 through the link 14.

Supported at each end of the step construction and secured to the side members 5 thereof, are the brackets 15 that are formed with bearings 16 to accommodate the shaft 17 that carries the segmental gears 18 at the ends thereof, the segmental gears 70 being keyed or otherwise secured to the shaft 17 to move therewith.

The lower end of the lazy tong 13 is pivotally mounted on the shaft 17, the lowermost arm in the lazy tong which is indicated at 17' being connected to the segmental gear 18 at one end of the shaft 17, whereby when the lazy tong is collapsed or extended, movement is imparted to the segmental gear 18 associated therewith. 80

The shaft 19 is also supported by the brackets 15 and carries gears 20 at the outer ends thereof, while at a point intermediate the ends of the shaft 19 is secured the pinion 21. Associated with the shaft 19 85 is a shaft 22 that is also supported by the brackets 15, the outer ends of the shaft 22 extending beyond the brackets 15 as clearly shown by Figure 2 of the drawings. This shaft 22 supports the racks 23 formed 90 with elongated openings 24 permitting of movement of the racks, the teeth thereof being in mesh with the teeth of the segmental gears 18 so that movement of the gears results in a relative sliding movement of the rack bars 23. 95

As shown, the gears 20 are also in mesh with the teeth of the rack bars 23 so that as the rack bars move, the gears 20 are also rotated rotating the shaft 19, on which 100 they are mounted. Mounted under the steps at a point intermediate the side edges thereof, is an operating arm 25 that has its intermediate portion supported by means of the pulley 26 mounted in the bracket 27, the lower end of the arm 25 being curved slightly upward at 28, where the same has pivotal connection with the extension step 29 as at 30.

Supporting arms 31 also have pivotal connection with the extension step 29, the arms 31 being formed with elongated openings 32

to accommodate the stub shafts 33 that are positioned within the cut out portions 34 formed in the outer surfaces of the side members 5 of the steps.

5. Formed at the opposite end of the arm 25 is a rack bar 35, the teeth thereof being in mesh with the pinion 21 so that as the pinion 21 is rotated, the rack bar 35 that is also moved to move the arm 25 and extension 10 step supported thereby into and out of operation.

In the operation of the device assuming that the door 7 has been moved to its open position, as shown by Figure 1 of the drawings. It is obvious that if the door 7 is moved downwardly to its closed position, the arm 10 moves upwardly moving the lazy tong to its extended position, with the result that the segmental gears 18 are moved in the 20 direction of the arrow in Figure 1 of the drawings.

It is obvious that as the segmental gears move as indicated, the rack bars 23 are also moved in the direction of the arrow, rotating the shaft 19. As the shaft 19 rotates, the pinion 21 is also rotated, moving the arm 25 upwardly which in turn carries the step 29 to a position in close proximity to the lowermost section 6 where the same is protected and held out of operation.

When the door 7 is moved to its open position, the operation as described is reversed, to the end that the step 29 is extended to a position as illustrated by Figure 1 of the 35 drawings.

What is claimed as new is—

1. In combination with the vestibule floor door of a car, an extension step operating mechanism including a lazy tong construction, means for connecting the lazy tong construction to the door to cause a relative movement of the lazy tong construction when the door is moved, an extension step, and means controlled by the movement of 45 the lazy tong for raising and lowering the step.

2. In combination with the vestibule floor door of a car, an extension step operating mechanism including a shaft on which 50 the door is mounted, a lazy tong construction having connection with the shaft, segmental gears adapted to operate by the movement of the lazy tong, rack bars movable by the movement of the segmental gears, an exten-

sion step, and means operated by the movement of the rack bars to move the extension step into and out of operation. 55

3. In combination with the vestibule floor door of a car, an extension step operating mechanism including a shaft on which the door is supported, bracket members, a shaft supported by the bracket members, a lazy tong, means for connecting the lazy tong and shaft, supporting the door, said lazy tong having connection with the shaft supported 60 in the brackets, segmental gears mounted at the end of the shaft supported by the brackets, an arm, an extension step pivotally supported at the lower end of the arm, and means for transmitting movement of the segmental gears to the arm for raising and lowering the extension step. 65

4. In combination with the vestibule floor door of a car, a shaft for supporting the door, a lazy tong supported adjacent to the shaft, and means for connecting the shaft and lazy tong to cause a relative movement of the lazy tong when the shaft is moved, a step supporting arm having a rack bar, a step pivotally supported at the lower end of the 70 step supporting arm, a rack bar forming a part of the bar, a shaft carrying a gear in mesh with the teeth of the rack bar, and means for transmitting movement of the lazy tong to the last mentioned shaft to raise 75 and lower the step supporting arm. 80

5. In combination with the vestibule floor door of a car and steps supported thereunder, an extension step operating mechanism, including a lazy tong construction, means for 85 transmitting movement of the door to the lazy tong, a step supporting arm supported under the steps of the car, means for transmitting movement of the lazy tong to the step supporting arm to raise and lower the 90 same, an extensible step, arms having connection with the step, said car steps having cut out portions formed therein, arms movable in the cut out portions and having connection with the step, said arms adapted 95 to move within the cut out portions, and means for supporting the arms. 100

In testimony that we claim the foregoing as our own, we have hereto affixed our signatures.

JESSE H. HARRISON.
MATTHEW WALKER.
